UNITED STATES PATENT OFFICE.

JOSEPH SCHENKER, OF MINNEAPOLIS, MINNESOTA.

SIGNBOARD.

Application filed January 8, 1923. Serial No. 611,424.

To all whom it may concern:

Be it known that I, JOSEPH SCHENKER, a citizen of the United States, resident of Minneapolis, in the county of Hennepin, 5 State of Minnesota, have invented certain new and useful Improvements in Signboards, of which the following is a specification.

This invention relates to new and useful 10 improvements in sign-boards and is more particularly directed to the provision of a sign-board which is of the type adapted to be employed for advertising purposes and erected along highways, railroad rights-of-way, etc. Such sign-boards must be of such 15 construction as to resist high wind pressures and must be braced, preferably without disfiguring the appearance of the sign-board. Furthermore, a desirable feature of 20 such sign-boards is to permit the employment of one or more panels which compose the display surface. Such panels are preferably demountable without destruction of 25 the frame and each may be made a component part of a single advertisement and be assembled to present a unitary panel structure.

The object therefore of this invention is 30 to provide an improved sign-board.

Other objects of the invention will more 35 fully appear from the following description and the accompanying drawings and will be pointed out in the annexed claims.

In the drawings there has been disclosed 40 a structure designed to carry out the objects of the invention but it is to be understood that the invention is not confined to the exact features shown as various changes may be made within the scope of the claims which follow.

In the drawings:

Figure 1 is a perspective view of the rear 45 of the sign-board with the underground supports shown in full lines;

Figure 2 is a vertical section on the line 2-2 of Figure 1;

Figure 3 is a perspective view of the front 50 of the positioned sign-board; and

Figure 4 is a cross-sectional view on the line 4-4 of Figure 1.

In the selected embodiment of the invention here disclosed, the sign-board includes broadly a pair of spaced uprights adapted to be supported in the ground or other base 55 and joined by a pair of opposed horizontal frame members which cooperate with the

uprights to provide a rectangular frame. Broadly, the portions of the sign-board intermediate the uprights are provided with hangers which are supported by struts to 60 provide a trussed structure.

The uprights 11 and 12 are similar and but one need be described in detail. For example, the lower end of the upright 12 is received within a recess upwardly presented by the sill 13. This sill is, in turn, mounted upon a lower sill 14 which is secured thereto and preferably extends at right angles thereto. The diagonal braces 15 are secured at their lower ends to the 70 outer portions of the lower sill 14 and, upwardly converging, are secured to the adjacent upright. The diagonal braces 16 are likewise secured to the outer portions of the upper sill 13 and to opposite portions of the 75 uprights which are here shown as rectangular in cross-section. These braced sill structures and the corresponding portion of the uprights are preferably embedded in the ground as is suggested by the ground-line 17 80 in Figures 1 and 2. The uprights are thus strongly braced against the usual wind pressures from various directions.

These spaced uprights are preferably made of relatively strong material, such as heavy 85 wood, and upwardly extend above the ground to form the upright or vertical sides of the sign-board framework. The form of sign-board here shown is rectangular and the top and bottom are formed by the horizontal frame members or beams 18 and 19. These beams are terminally received within recesses opposingly provided by the uprights as is shown by the dotted lines in Figure 1. The preferred means of locking these beams 90 and uprights together into a unitary frame is by means of the relatively long bolts 21 95 adapted to project through a boring extending transversely through the upright and longitudinally into the adjacent beam end portion as is shown in the detail view, Figure 4. The inner end portion of the beam boring extends through an angularly shaped recess 22 adapted to receive the nut 23 and to prevent its rotative movement therein. The 100 bolt 21 may therefore be inserted through the upright and beam borings and engage the nut 23 so that the two parts are securely held in assembled relation. The four corners are similarly assembled and held.

A pair of hangers are preferably supported in spaced relation intermediate the up-

rights, in substantial parallelism therewith, and are connected to the horizontal beams 18 and 19. These hangers are supported by diagonal struts from the uprights and 5 anchored in rigid spaced relation by one or more horizontal struts. The hanger 24 and the hanger 25 are similar and each is of a length upwardly to extend from the lower beam 18 to a point above the upper frame 10 beam 19.

The hanger 24, at its portion opposite the beam 19 to which it is preferably screwed or nailed as indicated, is provided with an inwardly and upwardly inclined recess which 15 terminates in a downwardly presented shoulder. The upper end portion of the strut is correspondingly tapered in order to be seated in the recess of the upright and its reduced end rests beneath the shoulder 20 whereby the hanger is supported in a substantially suspended relation. The lower end of the strut 26 is provided with an inclined or beveled face so that the lower end portion of the strut may be received within 25 a lower recess in the upright whereby the strut 26 is supported in its diagonal position. The other strut 27 is likewise supported by the upright 11 and, in turn, supports the hanger 25. These diagonal struts would 30 normally tend to thrust the upper portions of the two hangers and hence a compressive member such as a horizontal strut 28 is positioned between the two hangers adjacent their upper ends. This horizontal strut 28 35 terminally abuts against the opposed faces of the two hangers which are preferably rectangular in cross-section. The various frame members may be secured together by screws or nails as is suggested in Figure 1.

40 While the display surface of this sign board may be made of a single panel, it is preferable to provide a plurality of panels. Three such panels 31, 32 and 33 are here shown. These panels may be of sheet material or, as is preferred, of ceiling boards 45 of commercial form which are dovetailed together to form a unit. These units are of a vertical dimension so that they may be received between the relatively wide beams 18 and 19. A backing bar 34, of less width 50 than the beam 18, is nailed thereto adjacent the rear portion of the upper surface and extends longitudinally of the beam. This bar provides a stop against which the lower 55 marginal portion of the panel may rest and be supported as is indicated in Figures 1 and 2. The side backing bars 35 and 36 are similarly secured to the uprights 11 and 12, while the bar 37 is likewise secured to the 60 upper beam 19. These backing bars may be secured or nailed in assembled position.

Each panel has secured thereto adjacent its upper and lower margin a bar 38 similar to the backing bars 34 and 37 so as to provide means for interlocking the panel and

frame. The bars 38 are spaced from the upper and lower edges of the panels a distance substantially equal to the height of the backing bars 34 and 37. These bars may be screwed or nailed together, when the 70 panels are assembled to present a unitary display surface, as is indicated in Figure 2. It may be noted that the side bars 35 and 36 are shortened so as to permit the insertion of the end portions of the bars 38 between the side bars 35 and 36 and the backing bars 34 and 37.

A bracing bar is also preferably carried by each panel intermediate its upper and lower margins so that it extends in a horizontal direction when the panels are secured in assembled relation. For example, the panel 31 has secured thereto the bracing bar 39 which, when the panel is in position, extends from a recess in the side bar 35 of the upright to the middle portion of the front face of the hanger 25. A bolt 41 may secure the bar 39 to the diagonal strut 27 while the inner end is likewise bolted to the hanger 25. The bracing bar 42 of the middle panel 32 is also bolted at one end to the hanger 25 and extending horizontally across is bolted at its other end to the other hanger 24; while the bracing bar 43 of the panel 33 is bolted to the hanger 24 and terminally received in a recess in the other side bar 36. These horizontal bars function as struts to maintain the uprights and hangers in rigid and reinforced spaced relation and prevent distortion of the sign-board by wind pressure.

After the several panels are secured in assembled relation to the sign-board frame, a molding 44 is nailed or screwed to the beams 18 and 19 and the uprights 35 and 36 around the front margin of the panels to aid in holding the panels in position. And, this molding may be of the quarter-round commercial form shown in the drawings to present a more pleasing appearance to the display surface of the sign-board.

An auxiliary sign-board is provided by the upward extension of the hangers 24 and 25 above the upper horizontal frame member of beam 19. As shown, this auxiliary board is formed with a frame which is rectangular, the upper horizontal cap member being provided by the bar 45 while the sides are provided by the two strips 46 and 47. The elongated rectangular panel 48 is also provided with upper and lower marginal backing bars 49 adapted to be suitably secured to the bar 45 and beam 19 respectively.

There is thus provided a durable reinforced sign-beard. The emplacement of the strengthened sill structure completely underground avoids the necessity for disfiguring surface braces now commonly used by advertising service companies. The employment of the truss form of framework im-

parts inherent rigidity to the structure and the interlocking of the diagonal struts into the sides of the uprights and hangers prevents the entire frame from sagging in its center portion and obviates the necessity for center uprights. Furthermore, the provision of the removable panel structure permits a more economical use of this novel structure.

10 I claim as my invention:

1. A sign board including uprights at either end, said uprights being anchored beneath the top of the ground, a plurality of panels between said uprights, the middle 15 panel having on either side a hanger, struts extending from said hangers to said supports to support said hangers, a beam extending between said supports for supporting the lower end of said hangers and 20 panels between said supports and said hangers, and a panel between the hangers.

2. A sign board including uprights at either end thereof extending below the surface of the ground and anchored therein, 25 and an upper and a lower beam, the latter above the surface of the ground and both supported by said supports, hangers extending from the lower beam to points above the upper beam, struts extending from the 30 supports diagonally one to each hanger, braces extending horizontally from the supports to the hangers, and panels between the supports and the hangers and between the hangers.

3. A sign-board including a pair of spaced uprights extending beneath the surface of the ground and having anchors to prevent being blown down by the wind, a pair of spaced horizontal frame members extending 40 between and terminally secured to the uprights to form a substantially rectangular frame therewith, intermediate hangers extending between said frame members and adapted to be positioned in substantial parallelism with the uprights and connected to the horizontal members, and diagonal struts, the lower end of each strut being received within a recess in an upright and the upper end of each strut being received within a 45 recess in the upper portion of each hanger whereby the hangers are hung from the uprights and held in spaced relation by said horizontal frame members.

4. A sign-board including a pair of spaced 55 uprights extending beneath the surface of the ground and having anchors beneath said surface to prevent being blown down by the wind, a pair of spaced horizontal frame members extending between and terminally secured to the uprights to form a substantially rectangular frame therewith, intermediate hangers terminating at their lower 60 ends above the surface of the ground and adapted to be positioned in substantial parallelism with the uprights and connected to

the horizontal members, diagonal struts, each strut being supported at its lower end by an upright and adapted to support a hanger at its upper end whereby a trussed sign-board is provided, and a horizontal reinforcing frame member intermediate said spaced horizontal frame member and connected to the uprights, struts, and hangers. 70

5. A sign-board including a pair of spaced uprights extending beneath the surface of 75 the ground and having anchors at their lower ends to prevent being blown down by the wind, a pair of spaced horizontal frame members extending between and terminally secured to the uprights to form a substantially rectangular frame therewith, intermediate hangers terminating above the ground at their lower ends and adapted to be positioned in substantial parallelism with the uprights and connected to the horizontal 80 members, diagonal struts, each strut being supported at its lower end by an upright and adapted to support a hanger at its upper end whereby a trussed sign-board is 85 provided, and an auxiliary sign-board frame 90 provided by an upward extension of the hangers above the upper horizontal frame member.

6. A sign board including uprights extending below the surface and anchored to 95 prevent the sign board being blown down by the wind, upper and lower horizontal beams between the uprights, hangers extending from the lower beam upwardly above the upper beam, diagonal struts extending 100 from the vertical supports to the upper part of the hangers, panels between the supports and hangers and between the hangers, and horizontal bracing bars, attached to said struts, hangers and upright supports. 105

7. A sign-board including uprights, horizontal frame members carried by the uprights in spaced relation to provide a frame, a display-surface panel adapted to be received within the space defined by the uprights and frame members, and bars on the back of the panel adjacent its margin and adapted to be secured to the frame members whereby the panel may be removed without injury to the frame. 110

8. A sign-board including uprights, horizontal frame members carried by the uprights in spaced relation to provide a frame, backing bars carried by the uprights and members on their inner faces adjacent the 115 rear thereof, a display-surface panel adapted to be received within the space defined by the uprights and frame members and marginally to abut against said backing bars, and means to secure the panel to the backing bars. 120

9. A sign-board including uprights, horizontal frame members carried by the uprights in spaced relation to provide a frame, backing bars carried by the uprights and 125

members on their inner faces adjacent the rear thereof, a plurality of display-surface panels adapted to be received within the space defined by the uprights and frame members and marginally to abut against said backing bars, and bars on the back of the panels spaced from the marginal edges thereof a distance at least equal to the width of the backing bars whereby the outer faces of the panel bars may rest against the inner faces of the backing bars, and means to secure the panel bars to the backing bars. In witness whereof, I have hereunto set my hand this 5th day of January 1923.

JOSEPH SCHENKER.
